UNITED STATES PATENT OFFICE

2,216,266

TWO-STAGE OSCILLOGRAPH

Philo T. Farnsworth, Springfield Township, Montgomery County, Pa., assignor, by mesne assignments, to Farnsworth Television & Radio Corporation, Dover, Del., a corporation of Delaware

Application March 22, 1937, Serial No. 132,323

17 Claims. (Cl. 178—7.5)

My invention relates to oscilloscopes, and particularly to a two-stage cathode ray oscilloscope for television use, and embodies the broad principle of image amplification set forth in my prior application entitled "Electron image amplifier," Serial No. 461,110, filed June 14, 1930, now Patent No. 2,085,742, granted July 6, 1937.

Among the objects of my invention are: To provide a cathode ray oscilloscope of greater sensitivity; to provide a more efficient oscilloscope for television and other uses; to provide means for developing an amplified cathode ray beam within an oscilloscope; to provide a method of increasing the beam power within an oscilloscope available for image production for a given value of primary beam current; to provide means for producing a more brilliant visual image from a given primary beam; and to provide an oscilloscope wherein an electron beam is utilized to produce an incandescent line image, and said line image is utilized to produce an entire image of the televised subject.

Other objects of my invention will be apparent or will be specifically pointed out in the description forming a part of this specification, but I do not limit myself to the embodiment of the invention herein described, as various forms may be adopted within the scope of the claims.

My invention consists, briefly, in providing within an oscilloscope tube an incandescent electrode of width equal to that of the desired picture and height roughly equal to one picture element, across which each line of the picture to be produced shall in turn be scanned, whereby the electrode shall be incandescent in each elementary length thereof to a degree corresponding to the light intensity of the corresponding picture element: the incandescent line image thus produced, consisting of thermionic electron and secondarily emitted electrons, is in turn directed upon a viewing or projecting screen, with successive line images displaced from each other by a suitable deflecting field to form an entire image. By making the first electrode of highly emissive material, the number of electrons producing each element of the entire image may be increased without increasing the emission from the gun, and a more brilliant image may be thereby obtained without increasing the accelerating potentials or the size of the gun.

Referring to the drawing:

Figure 1 is a schematic sectional view of an oscilloscope employing my invention.

Figure 2 is a cross-sectional schematic view, taken along line 2—2 of Figure 1, showing the

structure of the intermediate electrode enlarged in proportion to the remainder of the tube.

The brilliance of an image produced in a cathode ray oscilloscope is dependent upon a number of factors, among which are the average number of electrons in the cathode ray beam and the construction of the screen upon which the image is produced. In the Farnsworth application entitled "Incandescent light source," Serial No. 67,889, filed March 9, 1936, now matured into U. S. Patent No. 2,089,054, issued August 3, 1937, it was pointed out that the essential requirements for brilliance in an incandescent screen are that the screen mass be small and that heat losses shall be by radiation rather than by conduction: in that application and in various related cases, a type of screen construction believed to offer a satisfactory answer to the problem was described, and the type of screen utilized in this oscilloscope is of the type therein set forth. The screen construction adopted is utilized also in an intermediate, line-width electrode, which by thermionic emission increases the average number of electrons in the cathode ray beam without requiring an increased primary cathode emission. This method is more efficient, since a large proportion of the energy lost in the tube is consumed in the cathode: the intermediate electrode, which acts as an additional cathode, provides increased electron emission at low energy loss, since the energy utilized therein is confined to the region of maximum emission per unit of power absorbed. This may better be understood by reference to the drawing, a more detailed description of which is as follows:

In Figure 1 I have shown a cathode ray tube embodying my invention. A long, evacuated, cylindrical envelope 1 of glass or similar insulating material is terminated at one end by a reentrant stem 2, and at the opposite end by an enlarged rounded head 4. An electron gun 5 is supported at the end of envelope 1 near the reentrant stem 2. In the figure, I have represented this gun conventionally as composed of a filamentary cathode 6 supported by leads 7 and 9 sealed through the press 10 terminating the reentrant stem 2, an apertured control electrode 11 supported by a lead 12 sealed through the press 10, and a gun-type anode 14 carried by a supporting lead 15 sealed through the wall of envelope 1. However, any combination of anode, cathode and control electrode which will produce a modulated electron beam is deemed a full equivalent of the gun 5, as shown.

When cathode 6 is heated by a battery 16 or

- equivalent source of energy, electrons are emitted therefrom and attracted toward anode 14 by a positive potential placed thereon by a battery 17, or an equivalent direct current source, through lead 15. The number reaching said anode is controlled in accord with a charge built up on the control electrode 11 by a signal current applied thereto through an input lead 19, condenser 20, and supporting lead 12. The gun 5 thus directs a signal-modulated beam of electrons along the axis of tube 1 in accord with well known practice, the electrons being accelerated by a positive potential produced by a battery 21 on an intermediate electron emitting electrode 22, diametrically disposed in a horizontal plane across envelope 1, as more clearly indicated in Figure 2. An electrostatic shield 24 covers the inner wall of envelope 1 from a point near the gun 5 to a point slightly beyond electrode 22, although insulated therefrom. By virtue of a connection 25 to the gun anode lead 15, shield 24 is maintained at anode potential, and prevents unwanted disturbance of the electrons traveling from gun to screen. This shield may be a metal cylinder inserted in the envelope, or may be formed by evaporating a conducting coat on the wall; a metal sleeve disposed about the exterior of envelope 1 would serve the same purpose.
- The modulated beam is caused to traverse electrode 22 by the magnetic field set up by diametrically spaced coils 26 (indicated schematically as one coil), connected to a sawtooth oscillator 27 tuned to the proper high scanning frequency, and the impact of the beam upon electrode 22 heats it to a degree of incandescent varying along its length in accord with the variable light intensity of the picture element in corresponding position. A battery 29 may be used to heat electrode 22 to a dull red glow, in order that all the energy in the beam may be utilized in producing visible changes. Otherwise, a considerable proportion of the beam energy would be wasted in heating the electrode to incandescence. If desired, this polarizing heat might be supplied by directing infra-red radiations upon the electrode 22 from a lamp, or an auxiliary gun might be provided to direct an unmodulated stream of electrons upon the said electrode.
- The electrode 22, in its preferred form, is formed by winding about 250 turns per inch of fine refractory wire, such as tungsten, upon a mandrel having a diameter of about .003 inch, and then etching the coil in hot sodium nitrite until the wire diameter is reduced to .00025 inch. It is supported by spot-welding the ends, under tension, to leads 23 and 28 sealed through the envelope 1. This method of forming a coil to be incandesced has been described in the pending Farnsworth application entitled "Incandescent light source," Serial No. 67,889, filed March 9, 1936, now matured into U. S. Patent No. 2,089,054, issued August 3, 1937, and as there pointed out, the efficiency is high, due to the small mass to be heated and the high percentage of heat loss by radiation as opposed to conduction.
- The electron line image thus produced, composed of secondarily emitted electrons thrown out by impact of the beam, and thermionic emission due to incandescence, is attracted along the tube toward a viewing or projecting screen 30, which is preferably formed of a number of coils similar to electrode 22, held parallelly in a plane in accordance with the teaching of the Farnsworth application, cited supra. Various other of the

applicant's screens may be used alternatively therewith, and are deemed full equivalents thereof.

The electronic line image from the intermediate electrode 22 is accelerated toward the projecting or picture screen 30 by a high positive potential from a battery 31 or equivalent source of direct current. The electron image components tend to spread out, due to the mutual repulsion of their negative charges, but are prevented from doing so by the field set up about solenoid 32 when energized by a battery 34. These magnetic focusing means cause the electrons to travel in mean rectilinear paths from electrode 22 to screen 30, and thus maintain the same relative intensity at screen 30 as at electrode 22. Successive line images are deflected by the field set up in diametrically placed coils 35, indicated schematically as a single coil, by sawtooth oscillator 36 operating at low scanning 20 frequency.

It will be noted that the high and low frequency scanning coils 26 and 35 are shown in Figure 1 as occupying nearly the same angular position about the axis of envelope 1, although their effect is exerted normal to each other. The reason for this position is found in the influence of solenoid 32. The field due to coil 26 traverses the beam horizontally along electrode 22, while the resultant field, due to coil 35 and 30 solenoid 32, produces a vertical deflection of the line image. The field of solenoid 32 may, depending on the strength of the current from battery 34 and the spacing of the parts, influence the field produced by coils 26. The resultant 35 field, which will be rotated about the axis of the tube to a degree dependent on the strength of the solenoid field component, would cause a deflection of the beam from gun 5 along a diameter at an angle to the horizontal. In practice, this is 40 corrected by rotating coils 26 about the tube until horizontal deflection is again secured; similarly, coils 35 may be rotated until the resultant field produces a vertical deflection of the line image. These adjustments may be checked visually by 45 maintaining a square image on screen 30.

Screen 30 may be polarized by means, not shown in the drawing, similar to those used with electrode 22, and the entire electronic impact utilized to produce an intensely incandescent image of the televised pictured or scene. The end 4 of the tube has been made large to provide ample heat radiating surface.

The incandescent image may be projected through a suitable focusing lens system 37, 55 shown schematically, upon a suitable viewing screen, not shown, or for direct observation.

In short, by forming upon an intermediate electrode successive incandescent line images, and utilizing these intense line images to produce the entire image, I am able to secure a much more intense image without increasing the beam power or raising the accelerating potential on the projecting screen, and am able to effect economies in operation while securing more intense images.

I claim:

1. A cathode ray oscilloscope comprising an evacuated envelope having therein a cathode, a control electrode, and a gun-type anode cooperating when energized as an electron gun to produce a modulated beam of electrons, an intermediate linear electrode capable of emitting electrons upon electron impact therewith positioned in the path of said beam, a two-dimensional 70

- screen capable of emitting light when bombarded with electrons from said linear electrode and positioned on the other side of said linear electrode from said gun, scanning means positioned 5 to move said modulated beam along the extent of said linear electrode to produce electron emission therefrom in accordance with the modulations of said beam, and a second scanning means positioned to move electrons emitted from said linear electrode across said second luminescent screen in a direction substantially at right angles to the motion of the original electron beam.
2. Apparatus as recited in claim 1, together with means for charging said linear electrode 15 positively relative to said anode, and means for charging said two-dimensional screen positively with relation to said linear electrode.
3. Apparatus in accordance with the recitation of claim 1, wherein the two-dimensional screen is 20 a screen incandescent upon electron impact therewith.
4. Apparatus in accordance with claim 1, wherein said linear electrode comprises a coil of refractory electron emitting wire of substantially 25 .00025 inch wire diameter, said coil having approximately 250 turns per inch with a coil diameter of substantially .003 inch.
5. A cathode ray oscilloscope comprising an evacuated envelope having therein a cathode, a 30 control electrode and a gun type anode, cooperating, when energized as an electron gun, to produce a modulated beam of electrons of elemental cross section, an intermediate electron emitting electrode extending across said envelope, aligned 35 with said gun anode and having dimensions corresponding to one picture line, means positioned to move electrons from said beam linearly and cyclically over the long dimension of said electron emitting electrode to produce heating thereof 40 and consequent electron emission, a picture screen capable of producing light upon electron impact therewith positioned in the path of electron emission from said electron emitting electrode, and a second scanning means positioned to 45 move electrons emitted from said electron emitting electrode across said picture screen to produce an image on said picture screen corresponding to the modulations of the modulated beam.
6. A cathode ray oscilloscope as recited in 50 claim 5, having a magnetic solenoid surrounding the electron path between the intermediate screen and the second screen.
7. A cathode ray oscilloscope as recited in claim 5, wherein the modulations of the initial 55 beam correspond to television signals, wherein the electron emission from the intermediate screen corresponds to a complete line of a television picture, and wherein the image on the second screen corresponds to the complete picture area.
8. A cathode ray oscilloscope as recited in 60 claim 5, wherein the first scanning means is a high frequency movement, and wherein the second scanning means accomplishes a low frequency scan movement.
9. In combination, a screen whose surface 65 emits light when bombarded with electrons, a thermionic cathode providing a stream of electrons directed at said screen, means for energizing said cathode to a temperature slightly less than that at which said cathode emits electrons in 70 substantial quantities, a source of picture signal modulated electrons, means for bombarding said cathode with electrons from said source to raise the instantaneous temperature of said cathode in accordance with the modulation of

electrons from said source, the electrons thereupon emitted by said cathode being modulated in accordance with said picture signals, and means for scanning said screen in a pre-determined pattern of lines with the stream of electrons emitted by said cathode to produce on said screen a visual image. 5

10. In combination, a screen whose surface emits light when bombarded with electrons, an elongated cathode providing along its length a stream of electrons directed at said screen, means for modulating the stream of electrons flowing from said cathode to provide at successive intervals of time electronic images of successive lines of a picture to be reproduced on said screen, 15 and means for sweeping said stream of electrons over said screen in a direction transverse to the axis of said cathode.

11. In combination, a screen whose incremental surface areas emit light when bombarded with electrons, a substantially linear cathode providing along its length a stream of electrons directed at said screen, means for modulating the stream of electrons emitted by said cathode to provide at successive intervals of time electronic 25 images of successive ones of a system of lines which together form a picture on said screen, and means for sweeping with substantially constant velocity said stream of electrons over said screen in a direction transverse to the axis of 30 said cathode.

12. The combination of a screen whose surface emits luminous energy when bombarded with electrons, an elongated cathode providing along its 35 length a stream of electrons directed at said screen, means for causing said electrons to bombard said screen, means for modulating the stream of electrons flowing from said cathode to provide at successive intervals of time electronic images of successive ones of a system of lines 40 which together form a picture on said screen, means for focusing said stream of electrons upon said screen as a line of finite length and optimum breadth, and means for sweeping said stream of electrons over said screen in a direction at an 45 angle to the axis of said cathode.

13. The combination, in a recording system, of a screen whose incremental surface areas emit light when bombarded with electrons, an elongated thermionic cathode providing along its 50 length a stream of electrons directed at said screen, means for energizing said cathode to a temperature slightly less than that at which said cathode emits electrons in substantial quantities, means for increasing the instantaneous 55 temperature of incremental lengths of said cathode to a temperature at which said incremental lengths of said cathode emit electrons in increased quantities, said last named means modulating the stream of electrons flowing from 60 said cathode to provide at successive intervals of time electronic images of successive ones of a pattern of lines which together form a picture on said screen, and means for sweeping said stream of electrons over said screen in a direction trans- 65 verse to the axis of said cathode.

14. In a recording system, the combination of a screen whose incremental surface areas emit light when bombarded with electrons, a cathode providing a substantially coplanar beam of electrons directed at said screen, a cross section of said stream in a plane parallel to said screen forming a line of finite length and optimum breadth, means for controlling the density of electrons at each incremental point in said 70 75

stream to provide at successive intervals of time electronic images of successive ones of a pattern of lines which together form a picture on said screen, and means for sweeping said stream of electrons over said screen in a direction transverse to the plane of said stream of electrons.

15. In combination, a screen whose surface emits light when bombarded with electrons, an elongated cathode providing along its length a stream of electrons directed at said screen, a second source of electrons, means for bombarding said cathode along its length with electrons from said second named source, the electrons from said second named source being modulated 10 through successive intervals of time in accordance with the light and shadow of successive ones of a pattern of lines which together form a picture to be reproduced on said screen, means responsive to the bombardment of said cathode 20 by electrons from said second named source for producing a modulation of the stream of electrons flowing from said cathode toward said screen to provide at successive intervals of time electronic images of successive ones of said pattern of lines which together form a picture on 25 said screen, and means for sweeping said stream of electrons emitted by said cathode over said screen in a direction transverse to the axis of said cathode.
- 30 16. In combination, a screen whose surface emits light when bombardment with electrons, an elongated cathode providing along its length a stream of electrons directed at said screen, a source of electrons modulated with picture sig-

nals, means for periodically sweeping said cathode along its length with modulated electrons from said second named source, each such periodical traversal of said cathode by said electrons effecting the modulation of the stream of electrons emitted by said cathode in accordance with the values of light and shadow along the length of a respective one of a system of lines which form the picture to be reproduced on said screen, and means for sweeping said stream of electrons 10 over said screen in a direction transverse to the axis of said cathode.

15. The combination, in a recording system, of a screen whose surface emits light when bombarded with electrons, a source of electrons modulated with picture signals, an elongated thermionic cathode providing along its length a stream of electrons directed at said screen, means for energizing said cathode to a temperature slightly less than that at which said cathode 20 emits electrons in substantial quantities, means for periodically sweeping said cathode along its length with modulated electrons from said first named source to increase the instantaneous 25 thermionic emission of elemental lengths of said cathode whereby said cathode emission is modulated in accordance with the values of light and shadow along corresponding elemental lengths of successive ones of a system of lines which together form a picture to be reproduced on said screen, and means for sweeping said stream of electrons over said screen in a direction transverse to the axis of said cathode.

PHILO T. FARNSWORTH.
